INSULATOR

Edwin M. Meyer, Parkersburg, W. Va., assignor
to Porcelain Products, Inc., Findlay, Ohio

Application June 2, 1933, Serial No. 674,093

6 Claims. (Cl. 173—321)

The invention to which this description relates consists in electrical insulators of the type in which a spool or knob of porcelain or other insulating material is held rigidly in place by a holder which is in the form of a screw-eye, bolt or the like. Such devices are used to hold the running part or an end of a wire conductor insulated or not. Under circumstances where this conductor is at the so-called dead end of a length there is considerable strain imposed upon the device due to the weight of the conductor and the tension with which it is fastened.

Insulators of this type are usually fastened to cross-arms, posts, walls or the like by means of wood screw-threads forming part of the device or a screw-threaded bolt and a cooperating nut. Due to the tension imposed upon such an insulator there is a marked tendency for the loop of the screw-eye to open under the tension to the point where the porcelain spool itself may drop out of the loop. One of the objects of my invention is to provide means for preventing the loop from opening under any operating condition. By the use of my design it has been found that the fixture will sustain several times the normal amount of tension required to open up the loops of ordinary screw-eyes and in fact permits me to utilize the maximum strength of the porcelain spool which will itself break before the screw-eye fails.

Another object of my invention is to provide the improved means by which the ends of the loops of the screw-eye are held together without possibility of disengagement.

It is an object of my invention to provide greater stability, increased mechanical strength and resistance to a pull at right angles to the axis of the screw by the use of an extended metal base. This base is a special form of the holding means for the ends of the loops of the screw-eye and combines the holding means with a base plate. In this way the base plate may be nailed into its final position on the support to prevent rotation and thus determine the angular position of the screw-eye. This will prevent the latter from working loose from the support. At the same time added reinforcement against lateral stresses in all directions is insured.

A further object of my invention is to utilize a large portion of the circular extent of the loop of the screw-eye as a bearing surface for the porcelain spool and convert the tension to a large extent into a pull or force longitudinally of the rod of which the screw-eye is formed. In other words, the ends of the loop of the screw-

eye are given directions tangential to the generally circular form of the bearing groove of the porcelain spool and thus minimize lateral stress on the material of the screw-eye.

Among the objects of my invention is the establishment of contact between the porcelain spool and the screw-eye so that there can be no relative rotation and thus there is avoided any possibility of the spool being turned during use under the influence of wind, swaying trees or the like which might otherwise cause objectionable creaking noise or wear.

The above and other objects of my invention will be apparent from the following description of the preferred embodiment of the invention as illustrated on the accompanying drawings in which

Fig. 1 is a side elevation of the screw-eye insulator;

Fig. 2 is an end elevation of the same, partly in section;

Fig. 3 is a perspective view of the fastening and holding link;

Fig. 4 is a longitudinal section of a modified form of the invention;

Fig. 5 is a side elevation of the invention applied with an extended base-plate;

Fig. 6 is an end elevation thereof;

Fig. 7 is a top view thereof and

Fig. 8 is a perspective view of the improved form of base.

By way of illustrating the invention and showing one of the forms which it may take, I have shown in the drawings a porcelain spool 5. This spool is made of glazed porcelain and given a form in which there is a flaring axial passageway 6 through which the service wire may be strung. Passageway 6 is flared at both ends as indicated in dotted lines in Fig. 2 so that the wire may be passed through and back upon itself to form a loop extending in any direction from the spool and without subjecting the wire to sharp edges which might cause wear or the destruction of insulation.

The mid-portion 7 of the spool is in the form of a groove which in Figs. 1 and 2 is illustrated as a true circle extending peripherally around the opening of the passageway 6 and equidistant therefrom. On each side of the groove 7 are end flanges 8, 8. These flanges may be of any convenient form although for purposes of improved electrical insulation they have been shown in Fig. 2 as having two spaced beads 9, 9.

One of the end flanges 8, 8 is split or transversely notched to form a recess 10. While this

recess is shown as passing entirely through the flange 8 it may be equally effective when limited to the inner part only.

The holding member for the porcelain insulating spool is a rod 11 which has been bent into the general form of a screw-eye having a screw-threaded shank 12 and a loop 13. This loop has one end 14 which is an integral extension of shank 12 while the opposite end 15 is brought back adjacent and parallel to the shank. The middle portion of the loop 13 is circular and conforms in final position with the middle portion 7 of the spool 5. The end portions 14 and 15 in meeting form substantially a right angle so that the pull on these ends is tangential to the circular parts of the loop and spool and practically axially of these looped portions.

A link 16 is formed of metal and has opposite ends 17 which are bent inwardly as shown in Fig. 3. The link 16 is applied to the ends of the loop in its position around the spool 5 and thus holds these loop ends firmly in contact against separation.

As illustrated in Figs. 2 and 3 the link 16 is provided with a lug 18 at the side opposite the open ends 17, 17. The lug 18 has a lateral extension 19 which conforms in position and extent to the recess 10 in the spool 5. When the link 16 is applied to the screw-eye, the detent 19 is within the recess 10 and thus prevents relative rotation of the screw-eye and spool.

In order to prevent accidental removal of the link 16 or the disengagement of detent 19 from the recess 10 I have shown the free end 15 of the loop to be bent laterally to form the end 20.

In the modification shown in Fig. 4 the spool 5 has the opening 6 and the end flanges 8 as already described. The middle portion is circular for substantially three-fourths of its periphery but the remainder is formed with an enlargement 21 which is bounded by intersecting faces substantially tangential to the inner wall of the groove 7.

This enlargement conforms quite closely with the axial relation between the ends 14 and 15 of loop 13. Link 16 holds the ends of the loop against accidental separation.

The insulator is assembled in any convenient manner with the link 16 holding the ends of the integral loop together. Either by reason of detent 19 or enlargement 21 the spool is prevented from relative rotation. The link 16 is prevented from sliding movement by the lateral bend 20.

The tension on the loop is applied throughout a relatively large circular area and is transmitted by the angular ends 14 and 15 directly and evenly to shank 12. In this manner the screw-eye will hold without deformation up to the full extent of the compression which the porcelain spool will sustain without fracture.

The porcelain spool is prevented from rotating in the screw-eye by the design thus described.

The form of the device as illustrated in Fig. 4 is capable of further development in respect to the link 16. This has been illustrated in Figs. 5 to 8 inclusive where the link 16 becomes a split collar 21. This collar is oval in cross-section as shown in Fig. 8 and one end of the oval is split to form the open ends 17, 17. The ends 17 are sufficiently short in extent so that during assembly they may be swaged or bent inwardly so that they meet and provide a close fit around the ends 14 and 15 of the loop of

the screw-eye 13. The extent of movement and the fit is illustrated in Fig. 5. In like manner it will be evident that the height of the ends 17, 17 is sufficient to extend substantially for the full distance between the outwardly turned end 20 and the bends in the loop ends 14 and 15.

The oval collar 21 forms the upstanding central part of a circular base-plate 22. This base-plate is made of sheet metal stamped or otherwise formed into final shape. The central portion of this plate is dished or flared over the greater part of its circumference to form sloping shoulders 23 which merge in the base and the collar 21.

The remaining portion of the base is relatively flat and has an upstanding flange 24 which completes the oval of the original form of the collar 21. This flange is sufficiently deep approximately to extend over the width of the end 20.

The flange 24 is separated from the ends 17, 17 by an open slot 25. The width of the slot is in a sense dependent upon the height of the flange and is essential only to insure that the flange be large enough to prevent turning of the end 20 and also to permit the ends 17, 17 to clear the upper edge of the end 20 in their closing movement.

This form of the invention is assembled as already indicated with the shank 11 and end 20 being inserted from above into the oval opening of the collar 21 until the end 20 is beneath the ends 17, 17 and opposite the flange 24. The ends 17, 17 are bent inwardly to meet tightly around the ends 14, and 15 of the loop 13 and thus prevent the latter from movement lengthwise.

The insulator is used in the usual manner by drawing up the screw end 12 into the support until contacted by the base-plate 22. A nail 40 driven into the notch 26 of the plate will prevent further angular movement of the plate and insulator. The screw-eye and insulator are held in final position without the possibility of working loose accidentally or changing their angular position.

While the preferred form of my invention has been described and illustrated for purposes of illustration, still any changes in details and parts may be made within the scope of the invention as defined in the following claims.

What I claim is:

1. An insulator comprising a spool having an axial wire-receiving passageway and parallel end flanges, one of said flanges having a recess, a holding member around the spool, and a detent carried by the holding member and engaging within said recess.

2. An insulator comprising a spool having an axial wire-receiving passageway and parallel end flanges, one of said flanges having a recess, a screw-eye having a loop around the spool, and separate means carried by said screw-eye for engaging within said recess.

3. An insulator comprising a spool having an axial wire-receiving passageway and parallel end flanges, one of said flanges having a recess, a screw-eye having a loop around the spool, means for fastening together the ends of said loop, and a detent on said fastening means for engaging said recess.

4. An insulator comprising a spool having an axial wire-receiving passageway and parallel end flanges, one of said flanges having a recess,

screw-eye having a loop around the spool, the ends of said loop meeting at a point eccentric to said loop proper, means carried by the meeting ends of the loop for fastening them together, and 5 a detent on said fastening means for engaging said recess.

5. An insulator comprising a spool having an axial wire-receiving passageway and parallel end flanges, one of said flanges having a recess, a 10 screw-eye having a loop around the spool, a link

around the ends of the loop and a detent on the link for engaging said recess.

6. An insulator comprising a spool having an axial wire-receiving passageway and parallel end flanges, one of said flanges having a recess, a 5 screw-eye having a loop around the spool, a link around the ends of the loop, one end of the loop being bent laterally adjacent the link, and a detent on the link for engaging said recess.

EDWIN M. MEYER. 10
